(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is the front view of a display screen or portion thereof with graphical user interface, showing my new design.

All other broken lines shown in the figures illustrate portions of a graphical user interface that form no part of the claimed design.
